His Attorney.

UNITED STATES PATENT OFFICE.

JONATHAN J. HOYT, OF CHELMSFORD, MASSACHUSETTS, ASSIGNOR TO
EDWARD F. RICHARDSON, OF SAME PLACE.

CASE FOR PRESERVING FOOD.

SPECIFICATION forming part of Letters Patent No. 296,692, dated April 8, 1884.

Application filed February 21, 1883. (No model.)

To all whom it may concern:

Be it known that I, JONATHAN J. HOYT, a citizen of the United States, residing at Chelmsford, in the county of Middlesex and Commonwealth of Massachusetts, have invented certain new and useful Improvements in Cases for Preserving Food, of which the following is a specification.

My invention relates to means for guiding the cover while being ground, and to means for securing the cover upon the case.

The accompanying drawing is a vertical cross-section through the center of all the parts described.

15 A is a cylindrical glass case, preferably of pressed glass, to secure uniform thickness of the walls and smoothness on the inside, and to avoid the sinking of a screw-thread on the inside of the glass corresponding to the thread

20 A², which inner thread, besides being of no use, would make it more difficult to remove the contents of the case when the contents were butter, lard, or articles of similar consistency and would also make trouble in cleaning the case.

25 Inside, the case is slightly larger at the top than at the bottom, to enable the plunger of the mold, in which the case is pressed, to be removed from the case, and this construction enables the contents of the case to be more easily removed. The case at the top is provided with an annular flange, A', and immediately below this flange is provided also with a screw-thread, A², which projects out from the case to a less distance than the flange projects.

35 The cover B is a circular glass plate, having a diameter equal to the largest diameter of the flange A', and the top of the flange and the bottom of the cover are ground together by any usual means, the cover being guided on the case in the operation of grinding by the ring C.

40 The ring C is passed up around the case from the bottom of the same, and has a screw-thread, C², which takes into the thread A² on the case A, and holds said ring C, or rather the shoulder

45 C' on said ring, up against the under side of the flange A'. Above the shoulder C' the ring C is enlarged and runs up straight above the flange A' and above the cover B, and is provided with an internal screw-thread, C², from the top of said ring C down to a point below

the top of the cover. Another ring, D, is provided with an external screw-thread, D², which takes into the thread C² of the ring C, so that the ring D may be turned down upon the top of the cover to hold the latter firmly against 55 the top of the case, or upon the top of any packing that may be interposed between said cover and case, the thread C² extending down low enough to allow the ring D to be turned against the cover, even if the cover is thinner 60 than intended to be. The lower thread, C², of the ring C is coarse, (about four threads to the inch,) to adjust said ring C quickly to place, while the threads C² and D² are fine, (about twenty threads to the inch,) to give great power, 65 the last-named threads C² D² being finer than could be made upon the glass case.

I prefer to make the ring D with an internal flange, D', which extends in toward the center of the cover far enough to give sufficient bearing-surface for the ring D, and thus to lessen the danger of breaking the edges of the glass cover. An external annular flange, D², on the top of the ring D extends beyond the ring C, and may be milled to assist in turning said 75 ring D up or down, to open or close the case. The cover is provided at or near the center with a conical hole or valve-seat, F, into which is inserted a conical glass valve, E, provided with a central opening filled by a plug, E', (of wood or metal,) having a threaded hole, E², into which a screw-pointed instrument may be inserted to draw the valve out of its seat. Said valve-seat and valve, being described in another application for a patent made by me and 80 now pending, are not claimed herein, except in combination with the case and cover, having their joining surfaces ground together. The valve and valve-seat are ground together as described in the application referred to. 90

Instead of an elastic gasket between the top of the case and the cover, I use a packing of refined soft paraffine-wax, which I barely melt and apply with a brush, sponge, or cloth to the top of the case and to the under side of the 95 cover at and near the edge of the same, these parts having been previously ground together to fit each other accurately. The ground surfaces of the cover and case thus coated with paraffine, being pressed together by the ring 100

D, as above described, make an air-tight joint by compressing and uniting the two films of paraffine-wax.

I have found by experiment that an air-tight joint cannot be made by pouring melted paraffine-wax into a channel or opening between the cover and case, because when thus applied the wax shrinks on cooling and admits the air. The packing described is clean and cheap.

15 The air is extracted from the case through the central opening in the cover, so that food may be put up cold in this jar, the means of extracting the air being an air-pump or a vacuum produced by steam. After the air is exhausted from the case, I cover the top of the valve and the projection with soft refined paraffine-wax, applied as above described, and lay thereon a piece of paper saturated with paraffine-wax. I protect the glass case and cover from breakage by a box, G, having a body, G', of pasteboard or equivalent material, saturated with hard paraffine-wax, (to exclude moisture from the pasteboard, and thereby prevent its becoming soft,) and having wooden ends I I'.
 20 These ends are made of wood to resist wear and for cheapness. The lower end, I, is provided with a recess, R, circular in form, to receive and hold the lower end of the case in the center of the box.

25 In the center of the central recess, R, is a depression, S, which lightens the box, and also allows the case to stand vertically in the box, when the bottom of the case has fallen or bulged downward from having been taken from the mold when too hot. This construction of the box allows the weight of boxes and cases, piled one above another, to rest on the vertical walls of the cases, instead of on the nearly horizontal and frequently uneven bottoms of the cases.

30 The top outer corner of the bottom is recessed at T to receive the lower end of the pasteboard G, which forms the sides of the box proper, the pasteboard being secured to the wood by brads and glue. The sides of the cover proper

are fastened to the upper end of the box in the same manner as the sides of the box proper are fastened to the bottom thereof. The upper end is recessed to admit the ring D, and rests only upon the flange D', being hollowed out centrally at D³, so as merely to touch lightly 50 the paper on the top of the valve.

It will be seen that the cover of the box is held centrally on the case by the projecting parts of said cover lying within and filling the vertical part of the ring D, and that the weight 55 of cases and boxes piled one above another rests upon the ring D above the vertical walls of the case A, instead of upon the central unsupported parts of the cover B, and that the case cannot move sidewise in the box. 60

I claim as my invention—

1. The combination of the case provided with an external screw-thread and a ring extending vertically above said case and having an internal screw-thread engaging with the 65 thread upon said case to guide the cover when being ground, as herein described.

2. The combination of the case A, provided with a screw-thread, A², the ring C, provided with screw-threads C² C³, the cover B, and the 70 ring D, provided with the screw-thread D³, as and for the purpose specified.

3. The combination of the case A, provided with the screw-thread, A² and flange A', the ring C, provided with the screw-threads C² C³ 75 and the shoulder C', the cover B, and the ring D, provided with a screw-thread, D³, as and for the purpose specified.

4. The combination of the case A, provided with the screw-thread A², the ring C, provided with screw-threads C² C³, the cover B, and the ring D, provided with the screw-thread D³ and flange D', as and for the purpose specified. 80

JONATHAN J. HOYT.
